(Cl. D7—4)

To all whom it may concern:

Be it known that we, Joe J. Marx and Fred J. Heckman, both citizens of the United States and residing at Wyoming and Cincinnati, respectively, in the county of Hamilton and State of Ohio, have invented a new, original, and ornamental Design for Toe Rubbers, of which the following is a specification, reference being had to the accompanying drawing, forming part thereof.

Figure 1 is a side elevational view showing our new design for toe rubbers.

Figure 2 is a top plan view thereof.

We claim:

The ornamental design for a toe rubber, substantially as shown.

JOE J. MARX.
FRED J. HECKMAN.
